UNITED STATES PATENT OFFICE.

ARTHUR ASHWORTH, OF BURY, ENGLAND.

VAT-DYEING MACHINE.

1,052,399.

Specification of Letters Patent. Patented Feb. 4, 1913.

Application filed July 15, 1911. Serial No. 638,678.

To all whom it may concern:

Be it known that I, ARTHUR ASHWORTH, a subject of the King of England, residing at Bury, Lancashire, England, have invented certain new and useful Improvements in Vat-Dyeing Machines; and I do hereby declare the following to be a full, clear, and exact description of the invention, such as will enable others skilled in the art to which it appertains to make and use the same.

This invention relates to dyeing apparatus, and more particularly to the vats used in dyeing with indigo or similar vat colors, and has for its object to overcome the objections common in the handling of such colors and to permit the indigo to be handled in a reduced condition.

Another object of the invention is to provide a device whereby the dyeing process may be accomplished in considerably less time than is consumed in the old methods.

Another object of the invention is to provide a device in which the oxidation of the dyeing liquid is reduced to a minimum and practically avoided.

A further object of the invention is to provide a dyeing vat with a sealed cover having a reduced inlet opening through which the fabric is passed into the vat and a similar exit for the fabric so that when the vat is filled with dyeing liquid there is no space for air to accumulate and oxidize the liquid. Further objects will be apparent from the following specification, appended claims and drawings thereof in which,

Figure 1 is a side elevation of the device, and Fig. 2 is a longitudinal sectional view therethrough.

Referring more specifically to the drawings there is shown a vat 10 of the usual construction mounted upon a base 11. The walls of the vat may be made of wood or metal as of common construction and secured to the bottom of said vat is a drain pipe 12 provided with the usual valve 13. The vat is provided with a cover 14 in which there is an inlet for the fabric as shown at 15 and an exit as shown at 16, these two openings as shown in the drawings are provided with a wall thereabout which extends a slight distance above the cover proper and above the inlet 15 is a roller 17 positioned as to deliver the fabric as indicated by the dot and dash line through the opening 15 as to avoid any friction on the walls of the opening 15 which would tend to injure the

fabric. The roller 17 is mounted in bearings 18 secured to the cover of the vat.

The fabric in passing through the vat containing the dyeing solution first passes between a pair of rollers 19 which are mounted in brackets 20 on the opposite walls of the vat so as to remove any air which may have accumulated in the fabric and the rollers 19 may be mounted in slideable bearings 65 having a spring to cause the rollers to bear firmly against one another or as I have shown one of the rollers may be mounted in a bearing having a downwardly inclined face which causes the roller to bear against the other roller, the fabric then passing about a plurality of rollers 21 mounted in the opposite walls of the vat so as to cause the fabric to take an up and downward path through the solution as shown in the drawings until it passes about the roller 22 of slightly greater diameter than the rollers 21 when it passes upwardly through exit 16 between rollers 23 and 24. The rollers 23 and 24 are slideably mounted in brackets 25 secured to the cover of the vat and the roller 24 has a covering of hard rubber or the like so that as the fabric is passed between the rollers the excessive liquid is squeezed therefrom, and the adjustment of the roller 24 is obtained by the hand-wheel 26 secured to the screw 27 which is mounted in a cross arm 28 and bears against the yoke 29 at each end of which is a further screw adjustment through the screws 30 which bear against the bearing blocks of the roller 24. The fabric, on leaving the rollers 23 and 24, then passes about the roller 31 which is mounted in bearings 32 secured to the brackets 25 and secured to the shaft 33 of the roller 23. 95

is a pulley 34 to which power may be applied in drawing the fabric through the vat. I provide a steam coil 35 which is placed in proximity to the bottom of the vat so that the liquid within the vat may be heated when desired. The cover 14 is also provided with a removable lid 36.

The operation of the device is as follows:—The fabric passes about the roller 17 through the opening 15 between the rollers 19 about the several rollers 21, roller 22 through the exit 16 between the rollers 23 and 24 and over the roller 31 where it is exposed to the atmosphere for a short time and then finally passed through an oxidizing bath. The vat is filled with dyeing liquid so that no air is permitted to accu-

mulate therein and the only portions of the liquid exposed to the oxidizing action of the air is the small amount at the opening 15 and exit 16 and it will be seen that the objections of the common methods are overcome by the exclusion of air from the vat.

In treating fabric in a damp state, I can fill the inlet and exit with an oil such as kerosene and thereby prevent even the oxidation of the dyeing solution about or within these openings or in other words hermetically seal the contents of the vat.

An important feature of my invention is the fact that the rollers 23 and 24 are mounted horizontally in relation to each other and not superposed as they appear in machines now common for this purpose.

Having thus described my invention, I claim:

- 20 1. A vat for dyeing comprising a chamber having a sealed cover, a reduced inlet and exit in said cover, a pair of squeezing rollers below said inlet, to exclude all air from any fabric entering said vat, a plurality of guide rollers within said vat and a second pair of squeezing rollers above said vat.
- 25 2. A vat for dyeing comprising a chamber

adapted to receive the dyeing liquid, a sealed cover for said chamber, a reduced inlet and outlet in said cover, a removable lid in said cover, rollers within said chamber to remove any air from fabric passing through said chamber rollers within said chamber to cause the fabric to take a prolonged course through said chamber and other rollers above 35 said chamber to remove any excess liquid from a length of fabric passing through said chamber.

3. In a dyeing apparatus, a vat having a sealed cover, an inlet and outlet through said cover, a plurality of guiding rollers within said vat, a pair of rollers mounted in said vat adjacent said inlet, the bearings of one of said rollers having inclined faces, and the roller mounted on said inclined faces impinging against the other rollers or an article therebetween by gravity.

In testimony whereof I affix my signature in presence of two witnesses.

ARTHUR ASHWORTH.
